UNITED STATES PATENT OFFICE.

PHILIP CHALLIS, OF LONDON, ENGLAND.

TRUNK-PISTON.

1,396,161.

Specification of Letters Patent.

Patented Nov. 8, 1921.

Application filed March 16, 1920. Serial No. 368,369.

To all whom it may concern:

Be it known that I, PHILIP CHALLIS, a subject of the King of England, residing at London, England, have invented certain new and useful Improvements in Trunk-Pistons, of which the following is a specification.

This invention has reference to trunk-pistons, more particularly intended for internal combustion engines but the invention 10 is applicable to pistons for steam and other engines. In these pistons, it is known to form the skirt with slots extending upward from the bottom with a view to obtaining a resilient lower portion to the piston.

15 The principal object of the present invention is to provide a piston the whole of the contact area of which is resilient, flexible, or yielding, the contact area being of such dimensions, and so positioned 20 immediately of the length of the piston as to prevent penetration of the oil-film under the cross-head resultant thrust. This is attained by providing the contact area with resilient, 25 flexible or yielding contact surfaces which in the free state are preferably of larger diameter than the bore of the cylinder. These contact surfaces are located substantially midway between the upper and lower ends 30 of the piston, so that the gudgeon pin from which the cross-head resultant pressure originates is comprised between the upper and lower limits of the contact area. The intermediate contact areas do not extend to the 35 lower edge of the piston skirt, but stop short of that edge; similarly toward the head end they stop short at such a point as to allow space for the accommodation of the piston rings or the like.

40 By the present arrangement, having the contact areas substantially midway of the length of the piston the latter is maintained at all times co-axial with the cylinder, without looseness of either the head or the lower end, and consequently no tilting of the piston 45 beyond that due to the yield of the resilient zones as the lateral thrust pressure varies, can take place to cause the piston to pivot and bring its head end violently across from one side to the other by reason of the transfer of the cross-head thrust.

The invention is hereafter described with reference to the accompanying drawings, in which:—

50 Figure 1 is an elevation of an alternative construction.

Figs. 2 and 3 are elevations in part section of other constructions.

Fig. 1 represents a form of piston in which the resilient areas are formed as tongues integral with the skirt of the piston but curved 60 outwardly so as to be normally of greater diameter than the body of the piston. In this construction the skirt is slotted on parallel lines d' extending for example over one fourth of the circumference, these slots being 65 connected by two opposite slots d^2 which are approximately parallel to the axis of the piston. The edges of the tongues forming the sides of the slots d^2 project beyond the general diameter of the piston, so that when 70 sprung into position in the cylinder they exert an outwardly expanding action against the cylinder wall, whereby the piston is held from tilting at the ends of its stroke or from chattering during the stroke. One or 75 more grooves may be cut, for example obliquely as indicated at j to retain lubricant and allow a sufficient degree of flexibility even when a thick gage of metal has been employed.

80 Fig. 2 shows a piston α having an attached sleeve c which is slotted at d to afford resilience in a radial direction to facilitate circumferential expansion and contraction. The sleeve is attached by screw threads c' 85 at one extremity, its other extremity c^2 being free. The slotted portion is of larger diameter than the head end of the piston α , but when inserted in the cylinder the enlarged portion is collapsed to a diameter 90 substantially equal to that of the cylinder. The slots d do not extend to the extremity c^2 forming the lower edge of the piston; such edge remains continuous and is of narrower diameter than the enlarged portion of the 95 sleeve. Certain of the slots may intersect or meet at their extremities, so as to afford flexible tongues c^3 , and they may be of the same width throughout or wider at certain points of their length. The slots may be 100 ended by transverse perforations d^3 through the sleeve or trunk of the piston, and these holes may be used for connecting together two or more slots as stated above.

105 Fig. 3 represents a similar construction in which two aligned sleeves c are provided, both being slotted at d to afford resilience. The upper and lower sleeves are attached to the piston body by screw threads c' at their adjacent extremities, the upper end c^2 of the up- 110

per sleeve being free to slide upon its supporting surface, and the continuous outer end c^2 of the lower sleeve being free. The slots d are preferably arranged obliquely to 5 the axis of the piston and of opposite hands in the two sleeves; certain of the slots intersect or meet so as to afford flexible tongues c^3 , as in the previous construction.

In all cases the diameter of the piston 10 as measured upon the longitudinal plane through the gudgeon pin may be less than that perpendicular to it; the shorter diameter may be over the size of the cylinder or there may be clearance in this direction, the 15 object of the invention being still sufficiently usefully secured by the elimination of clearance at the faces taking the cross-head resultant pressures.

What I claim is:—

20 1. A piston, comprising a head, a body portion, guide-surfaces supported from said body-portion, said guide-surfaces being slotted on intersecting lines, to form flexible tongues between the slots in said guide-surfaces, said tongues extending alternately up and down the length of the piston and projecting radially beyond the unslotted portions of said guide surfaces.

2. A piston, comprising a head, a body 30 portion, guide-surfaces supported from said body-portion, said guide-surfaces being slotted longitudinally in an oblique direction and the opposite ends of alternate slots connected by intersecting slots, to form flexible 35 tongues between the slots in said guide-surfaces, said tongues projecting radially beyond the unslotted portions of said guide-surfaces.

3. A piston, comprising a head, a body- 40 portion, guide-surfaces supported from said body-portion, said guide-surfaces being slotted on intersecting lines which stop short of the ends of said guide surfaces, to form flexible tongues between the slots in said 45 guide-surfaces, said tongues projecting radially beyond the unslotted portions of said guide-surfaces.

4. A piston, comprising a head, a body- 50 portion, guide-surfaces supported from said body-portion, said guide-surfaces being slotted obliquely on intersecting lines to form flexible tongues between the slots in said guide-surfaces, said tongues extending lengthwise of the piston and projecting radially beyond the unslotted portions of said 55 guide-surfaces.

5. A piston, comprising a head, a body- 60 portion, means for the attachment of a piston pin, guide-surfaces adapted to slide on the walls of the cylinder, said guide-surfaces

being slotted obliquely on intersecting lines which stop short of the ends of said guide-surfaces, to form flexible tongues between the slots in said guide-surfaces, said tongues extending lengthwise of the piston above 65 and below the level of said attachment means and projecting radially to a diameter greater than that of the cylinder.

6. A piston, comprising a head, a body-portion, means for the attachment of a piston-pin, guide-surfaces connected to said body-portion, said guide-surfaces being divided into zones and each of said zones being slotted on intersecting lines which stop short of the boundaries of said zones, to form flexible tongues between the slots in said guide-surface zones, said tongues extending above 75 and below the level of said attachment means and projecting radially beyond the unslotted portions of said guide-surface zones. 80

7. A piston, comprising a head, a body-portion, a sleeve secured to said body-portion, said sleeve being of slightly smaller diameter than the cylinder and being slotted lengthwise on intersecting lines which stop short of the ends of said sleeve, to form flexible tongues between the slots in said sleeve, said tongues projecting radially beyond the unslotted portions of said sleeve. 85

8. A piston, comprising a head, a body-portion, means for the attachment of a piston-pin to said body-portion, a sleeve secured internally at about the level of said attachment means to said body-portion, one end of said sleeve being slidably engaged upon said body-portion, said sleeve being divided into zones above and below the level of said attachment means, said zones being slotted obliquely on intersecting lines, to form flexible tongues between the slots in said zones, said tongues projecting radially beyond the unslotted portions of said sleeve. 95 100

9. As a new article of manufacture, a piston having a skirt in the form of a sleeve with flexible tongues affording equalized 105 local pressure on the cylinder walls throughout the whole area of its circumference.

10. As a new article of manufacture, a piston having a skirt in the form of a sleeve with intersecting slots extending above and below the level of the piston pin and providing flexible tongues, said tongues bearing uniformly upon the cylinder walls throughout the circumference of said slotted sleeve. 110

In testimony whereof I have affixed my 115 signature in presence of two witnesses.

PHILIP CHALLIS.
